US00D916125S

(12) **United States Design Patent** (10) Patent No.: **US D916,125 S**
(45) Date of Patent: **** Apr. 13, 2021**

(54) **DISPLAY SCREEN OR PORTION THEREOF WITH ICON**

(71) Applicant: **Samsung Electronics Co., Ltd.**, Suwon-si (KR)

(72) Inventors: **Saemyuk Sheen**, Suwon-si (KR); **Jaehan Lee**, Suwon-si (KR); **Hankyung Jeon**, Suwon-si (KR)

(73) Assignee: **SAMSUNG ELECTRONICS CO., LTD.**, Suwon-si (KR)

(**) Term: **15 Years**

(21) Appl. No.: **29/713,229**

(22) Filed: **Nov. 14, 2019**

(30) **Foreign Application Priority Data**

Jul. 31, 2019 (KR) 30-2019-0036632

(57) **CLAIM**

The ornamental design for a display screen or portion thereof with icon, as shown and described.

DESCRIPTION

The single FIGURE is a front view of a display screen or portion thereof with icon showing our new design.

The broken line showing of a display screen or portion thereof forms no part of the claimed design.

1 Claim, 1 Drawing Sheet
